CLAIM

The ornamental design for a laundry appliance door, as shown and described.

DESCRIPTION

FIG. 1 is a front perspective view of a laundry appliance door showing my new design;

FIG. 2 is a front view thereof;

FIG. 3 is a right side view thereof;

FIG. 4 is a left side view thereof;

FIG. 5 is a top view thereof; and,

FIG. 6 is a bottom view thereof.

The broken lines shown in the figures is for the purpose of illustrating portions of the laundry appliance door that form no part of the claimed design. The contrast in shading techniques represents a contrast in appearance and does not represent any particular color, texture, or finish.
